UNITED STATES PATENT OFFICE.

WALTER BROADBRIDGE AND ALLEN CRAWFORD HOWARD, OF LONDON, ENGLAND,
ASSIGNORS TO MINERALS SEPARATION LIMITED, OF LONDON, ENGLAND.

APPARATUS FOR ORE CONCENTRATION.

1,084,196.

Specification of Letters Patent.

Patented Jan. 13, 1914.

Application filed June 23, 1913. Serial No. 775,393.

To all whom it may concern:

Be it known that we, WALTER BROADBRIDGE and ALLEN CRAWFORD HOWARD, subjects of the King of England, and residing 5 in London, England, have invented certain new and useful Improvements in Apparatus for Ore Concentration, of which the following is a specification.

This invention is for improvements in or 10 relating to apparatus for ore concentration and more particularly to apparatus for carrying out the well known agitation-froth flotation process as described for example in the previous United States Patents No. 15 835,120, to Sulman, Picard and Ballot, November 6, 1906, No. 962,678, to Sulman, Greenway and Higgins, June 28, 1910, and No. 1,064,723, to Greenway and Lavers, June 17, 1913.

20 The apparatus is a development from that described in the previous United States Patents Nos. 953,746, to T. J. Hoover, April 5, 1910, and 979,857 to T. J. Hoover, December 27, 1910, and comprises a series of mixing 25 and aerating vessels each containing a rotary agitator, and a series of spitzkastens contiguous thereto and communicating therewith.

This invention is particularly applicable 30 between the spitzkastens of partitions which do not extend up to the liquid level so as to leave one uninterrupted surface for the formation of the froth.

This invention is particularly applicable 35 in combination with the apparatus described in the previous United States Patent No. 1,064,209, to J. Hebbard, June 10, 1913.

Apparatus embodying the present invention 40 may comprise a series of agitating and aerating vessels, substantially on the same level, a series of spitzkastens also on the same level and contiguous thereto but staggered in relation to the agitating vessels, a high level outlet from each agitating vessel (or group of agitating vessels) to the next 45 spitzkasten and a low level outlet from that spitzkasten to the bottom of the next agitating vessel, the partitions between the spitzkastens terminating below the liquid level in the spitzkastens so that there is one liquid 50 surface common to the whole of the spitzkastens on which surface the froths formed at all parts of the apparatus collect.

Where several agitating vessels are coupled together to form a group and discharge

into one spitzkasten, or where a single agitating vessel discharges into a spitzkasten, it is convenient to employ the term "section" as meaning either such an agitating vessel or a group of agitating vessels.

Referring to the form of apparatus described in the previously mentioned United States patent to Hebbard, No. 1,064,209, we find it convenient in applying this invention thereto, to employ two or more agitating vessels to each spitzkasten. Thus the pulp 60 in its travel through the apparatus may pass through three agitating vessels, then through one spitzkasten, then through two agitating vessels and one spitzkasten and again through two agitating vessels and one 65 spitzkasten and so forth, each such group of agitating vessels forming a section. We have also found it advantageous to apply 70 this invention in conjunction with the apparatus described in the British patent to 75 Howard, No. 22,743 of 1912. In that patent it is proposed to employ a grid within the mixing vessel to obstruct the rotation of the pulp therein.

As a feature of the present invention we 80 find it advantageous to employ a grid at the outlet only of each mixing vessel. This grid consists of a series of vertical plates or 85 projections spaced apart and with vertical flat faces so placed as to obstruct the rotation of the pulp and direct it outwardly through the grid and the result is that the grid acts as a series of baffles to increase the agitation and aeration, and also acts as a pulp directing outlet for the agitated pulp, 90 delivering the latter in a series of streams into the spitzkasten so that the pulp thus delivered into the spitzkasten will flow toward the front end of the spitzkasten and a full opportunity will thus be afforded for the 95 flotation in the spitzkasten of the froth potentially formed in the pulp by the agitation to which the pulp has been subjected.

The following is a description of one form 100 of apparatus embodying this invention, and in the accompanying drawings: Figure 1 is a perspective view of the apparatus partly in section, Fig. 2 is a plan and Fig. 3 is a sectional side elevation on the line 3—3 of Fig. 2.

105 The series of agitation and aeration vessels A¹, A², A³, A⁴, A⁵, A⁶, etc., are arranged side by side and preferably on the same level.

These are coupled together in groups or pairs, each such group or pair constituting a section, that is to say, the first, second, and third vessels, A¹, A², A³ are connected by orifices B¹ and B²; the fourth vessel A⁴ is connected to the fifth A⁵ by an orifice B³ and so forth, and these orifices may be provided with grids K, which project into the mixing vessels and act as baffles therein. These agitation and aeration vessels A¹, A², A³, A⁴, 10 A⁵, A⁶, etc., may consist of one long wooden box C divided by vertical partitions D¹, D², D³, D⁴, D⁵, D⁶, etc., into separate vessels. Each such vessel is provided with an agitator E preferably of the type described in the 15 previously mentioned British Patent, No. 22,743 of 1912, to Howard, and agitators of this type are indicated in the drawings of the present application. Along side of the 20 agitation and aeration vessels are a number of spitzkastens F¹, F², F³, F⁴, conveniently one for each section or group of agitation vessels. These spitzkastens are substantially 25 on the same level as the mixing vessels, i. e., with the bottoms of the spitzkastens sloping up from the bottoms of the agitation vessels. These spitzkastens are staggered in relation to the groups of agitation vessels, i. e. the first spitzkasten F¹ contacts with the second 30 and third agitation vessels A² and A³, belonging to the first section or group of these vessels and with half of the fourth A⁴. The second spitzkasten contacts with the fourth and fifth agitation vessels A⁴ and A⁵, belonging 35 to the second section of the vessels, and a half the sixth A⁶, belonging to the third section and so on. At a convenient point in the height of the third agitation vessel A³ say half way up, is a high level orifice G 40 leading to the first spitzkasten. This orifice preferably consists of a grating K, the bars or plates of which project into the agitating vessel and act as baffles therein and also act to direct the pulp as it flows from the agitating vessel to the spitzkasten. The extent of 45 the outlet may be required by a plate covering a portion of the grating. At the bottom of the first spitzkasten is a low-level orifice H leading into the bottom of the fourth mixing vessel A⁴ and so on. Each spitzkasten is 50 thus provided with two orifices, one at a high level by which the agitated pulp is passed from one agitation vessel to the spitzkasten and the other at a lower level by 55 which the pulp which sinks passes to the next agitation vessel in the series.

The main feature of this invention lies in the fact that the partitions J¹, J², J³ between the spitzkastens do not extend up to the 60 level of the liquid in the spitzkastens so that the froths which form in all the spitzkastens have one common liquid surface at which they collect and from which they flow into a launder L or launders for the concentrates. 65 A rotatable froth-removing paddle M may

be provided at the overflow lip of the spitzkastens to facilitate the discharge of the froth into the launder L.

The advantageous results of this invention are to simplify the apparatus as a whole, to 70 obviate the friction and obstruction which arise when the spitzkastens are completely separated from one another and to allow the froths to be automatically adjusted to comparative uniformity. In carrying out the 75 agitation-froth process in the usual way, the greatest froth is formed on the first spitzkasten and it is common for the quantity and coherence of the froth to diminish as the pulp proceeds through the apparatus, 80 but with the apparatus above described the whole spitzkasten surface is available for the collection and separation of the froth and thus any overloading of one or more spitzkastens is avoided, and the froth as a 85 whole has a more uniform opportunity of rejecting any gangue accidentally taken up with it, and the froth, as a whole is more mobile and can flow more freely away from the spitzkastens into the launders. It will 90 be seen that in this apparatus pipes, valves, or attachments between the different parts of the apparatus are entirely dispensed with.

What we claim as our invention and desire to secure by Letters Patent is:— 95

1. The herein-described apparatus for carrying out the agitation-froth process of ore concentration comprising in combination a series of agitating and aerating vessels, a series of spitzkastens contiguous thereto and 100 communicating with a plurality of the said vessels at various points, and partitions between the spitzkastens which do not extend up to the liquid level, so as to leave one uninterrupted surface for the formation of the 105 froth.

2. The herein-described apparatus for carrying out the agitation-froth process of ore concentration comprising in combination a series of agitating and aerating vessels, a 110 series of spitzkastens contiguous thereto and communicating with a plurality of the said vessels at various points, but staggered in relation to the agitating and aerating vessels, and partitions between the spitzkastens 115 which do not extend up to the liquid level, so as to leave one uninterrupted surface for the formation of the froth.

3. The herein-described apparatus for carrying out the agitation-froth process of ore 120 concentration comprising in combination a series of agitating and aerating vessels arranged in sections, a series of spitzkastens contiguous thereto and communicating with a plurality of the said vessels at various 125 points, but staggered in relation to the agitating and aerating vessels, a high level outlet from each section to the next spitzkasten and a low level outlet from the spitzkasten to the bottom of the first agitating vessel of 130

the next section, and partitions between the spitzkastens which do not extend up to the liquid level, so as to leave one uninterrupted surface for the formation of the froth.

- 5 4. The herein-described apparatus for carrying out the agitation-froth process of ore concentration comprising in combination a series of agitating and aerating vessels arranged in sections, a series of spitzkastens contiguous thereto and communicating with a plurality of the said vessels at various points, but staggered in relation to the agitating and aerating vessels, a high level outlet from each section to the next spitzkasten,
- 10 15 a grating in such outlet having bars or plates which project into the agitating vessel, a low level outlet from the spitzkasten to the bottom of the first agitating vessel of the next section, and partitions between the spitz-
- 20 kastens which do not extend up to the liquid level, so as to leave one uninterrupted surface for the formation of the froth.

5. The herein-described apparatus for carrying out the agitation-froth process of ore separation comprising, in combination, a series of agitating and aerating vessels arranged in sections, a series of spitzkastens contiguous thereto and communicating with a plurality of the said vessels at various points, an outlet from each said section to the next spitzkasten, a grating in each such outlet having bars or plates forming pulp-directing baffles, and an outlet from the spitzkasten to the first agitating vessel of the next section.

In testimony whereof we have signed our names to this specification in the presence of two subscribing witnesses.

WALTER BROADBRIDGE.
ALLEN CRAWFORD HOWARD.
